GAME DEVICE FOR TICK-TACK-TOE

Stanley J. Greif, Los Angeles, Calif.

Application June 8, 1953, Serial No. 360,109

1 Claim. (Cl. 273—130)

My invention relates to circular rotating discs and moveable slide-rules in combination; also to score-card recording means, and more particularly to an automatic device for playing the game of tick-tack-toe without an opposing player.

The game of tick-tack-toe has always been quite fascinating and wit-matching to both young and old, and in this age of robots and mechanical thinking machines my midget brain toy-game is especially entertaining and amusing, besides being very simple and comparatively inexpensive to construct. An advantage in the construction of the device is the use of such common materials as card-board, fibre-board, plastics, or any other such desirable materials. This AUTOmatic game of ticTACtoe that I call AUTO-TAC will always win or tie and never lose against any player.

An object of this invention is to bring the game of tick-tack-toe down to its simplest form and lowest number of mathematically determined pattern combinations, which this device has successfully accomplished.

Another object is to provide an apparatus with a rotating circular disc and a vertical slide rule in combination to aid in the display of a limited series of numerical scales and numerical determined patterns.

A further object is to provide a simple and effective means for recording the moves in the game on an improved permanently mounted score-board, and for lighting clearance of the score-board to begin a new try at beating the machine.

Still further objects will make themselves apparent from the description of the device that follows.

I attain these objects by mechanism illustrated in the accompanying drawings, in which—

Figure 1 is a rectangular face-card or face-board;

Fig. 2, a narrow vertical slide-rule, card or board;

Fig. 3, a magic slate score-card; and

Fig. 4, a rotating circular card or disc.

In detail, Fig. 1 represents the face card with its adjoining and connecting parts outlined. Slots 1 and 1' accommodate the vertical slide-rule; window 2 is covered by part of the vertical slide-rule, and helps to display the numerical patterns printed in the eight sectional boxes on the circular card, one horizontal line at a time, as provided by the limited window space inside the body of the arrow on the vertical slide-rule; window-A displays the scale-A numbers in the first move by the player as he rotates the circular card; window-B, directly above window-A, displays the scale-B numbers, one at a time, which are the device's first countermoves to the player's first or A-moves; the scale-C numbers are printed directly on the face card as shown, from which the player chooses his second move, and in order to disclose the device's next countermove the player moves the vertical slide-rule until the head of the arrow on it points to the number he has chosen, thereby revealing the countermove as scale D seen through the horizontal window inside the arrow at the extreme left.

Fig. 2 depicts the vertical slide-rule with point 1 on the

2

head of the arrow and window 2 inside the shaft of the arrow. For the final move on the indicated scales, the player chooses a number on scale-E printed along the lower border of the arrow and then looks for the device's last countermove to it directly above the number so chosen as it appears inside window-2 as one of a horizontal row of numbers. If the game has not here, or on the earlier move, terminated with a win for the device, the player has demonstrated good playing ability by bringing it to a tie or draw.

Fig. 3 shows the recording or score-card with the standard scheme of nine boxes imprinted on the underside of a transparent overlay. For purposes of identification the boxes have been numbered consecutively from 1 through 9 as shown. The boxes may be given other identifying figures or letters. The novel transparent overlay with the indelibly printed classical design of nine boxes together with the permanent X-mark of the device's first move in box-3 is attached to the surface of a so-called "magic slate" which consists of a base of black gummy wax and a milky cellophane cover, the latter becoming attached to the former at points where any writing or inscribing is done.

Fig. 4 contains all of the countermove schemes of numbers and the eight corresponding determined patterns that together constitute the distinguishing automatic feature of the game. The larger circle of A-figures make up the scale-A numbers from which the player chooses his first move. After he has done so and has brought the chosen number into window-A by rotating the circular card, a corresponding number from the smaller scale-B circle of numbers will simultaneously make its appearance through window-B on the face card. This number is the device's first countermove. The player then moves to scale-C (Fig. 1) for his next chosen box number or move. He raises the vertical slide-rule until the head of the arrow on it points to the chosen number, and reads the simultaneously appearing number inside the horizontal window along the arrow-shaft and under the arrow-point of scale-D. After recording these moves in the appropriate boxes with "O"-marks for the player and "X"-marks for the countermove, it then remains for the player to make the final move on scale-E and look for its countermove in the window directly above it. These final countermoves make up the eight determined patterns of numbers that go into the eight designated sections on the circular card, marked P-1 through P-8.

The following scheme of eight groups of determined patterns are the result of the device's permanent first move in box #3, which by symmetry can also be any one of the four corner boxes:

GROUP I (P-5)

(All box numbers based upon Fig. 3)

Device's first move—box #3 (permanent)
 Player's first move—box #1 (window "A")
 Device's first countermove—box #9 (window "B")
 Player's second move—any remaining box number on scale-C

Scale-C	Scale-D	Scale-E
1		
2	6	
4	6	
5	6	
6	7	8 8 8 5
7	6	
8	6	
9		

Device's second countermove in scale-D next to player's second move on scale-C

3

Player's third move selected from remaining boxes under scale-E

Device's third countermove obtained by reading number from row determined by player's second move (scale-C) and column determined by player's third move (scale-E). The intersection of the row and column is the device's third countermove

This group I is terminated by a win for the device either before or at the time of the third countermove

GROUP II (P-6)

Device's first move—box #3 (permanent)

Player's first move—box #2 (window "A")

Device's first countermove—box #5 (window "B")

Player's second move—any remaining box number on scale-C

9	7

1 2 4 5 6 7 8 9
Scale-E

Device's second countermove in scale-D next to player's second move on scale-C

Player's third move selected from remaining boxes under scale-E

Device's third countermove obtained from intersection of the row made by player's second move (on scale-C) and the column obtained from the player's third move (on scale-E)

This group II is terminated by a win for the device either before or at the time of the third countermove.

GROUP III (P-7)

Device's first move—box #3 (permanent)

Player's first move—box #4 (window "A")

Device's first countermove—box #9 (window "B")

Player's second move—any remaining box number on scale-C

4
Information on determination of second and third countermoves same as for group I

If the game is not terminated after the third countermove, then the player makes his fourth move by selecting one of the two remaining boxes. The device's fourth countermove is the last remaining box

The results of group IV will be either a win for the device or a draw

GROUP V (P-1)

Device's first move—box #3 (permanent)

Player's first move—box #6 (window "A")

Device's first countermove—box #5 (window "B")

Player's second move—any remaining box number on scale-C

Information for determining second and third counter-moves same as for group I

I claim:

In combination, constituting an automatic game device of tick-tack-toe, a circular disc containing appropriately imprinted numerals arranged within eight symmetrical sections as shown, centrally grommeted to a face-plate for rotation; two windows in the face-plate to have one window for a player's first selected move and the other window

dow for a countermove; a third window larger than said two windows in the face-plate for viewing the counter-moves; a numerical scale imprinted on the face-plate adjoining the third window for the player's second move selection; two grooves cut into the face-plate one above and one below the larger window for the accommodation of a supplementary vertical slide to move in and out of the face-plate within the same plane of the face-plate; a scale imprinted on the vertical slide for the player's third move selection.
